United States Patent Office.

ALEXANDER WEMYSS, OF PHILADELPHIA, PENNSYLVANIA, ASSIGNOR TO DAVID STUART AND RICHARD PETERSON, OF SAME PLACE.

Design No. 3,564, dated June 29, 1869.

DESIGN FOR THE FRAME OF A FIRE-PLACE.

The Schedule referred to in these Letters Patent and making part of the same.

To all whom it may concern:

Be it known that I, ALEXANDER WEMYSS, of Philadelphia, county of Philadelphia, and State of Pennsylvania, have originated a new Design for a Frame for Fire-Place Stoves; and I do hereby declare that the accompanying drawing, and following explanation thereof, form a full, clear, and exact description of the said design.

In the drawing, the figure represents the design for the frame of a fire-place stove, the said frame consisting of a plate, the outer edge of which is defined by the arched top *a* and perpendicular lines *b b*, the inner edge being also arched at the top *d*, which meets the protuberances *e e*, with gradual curves at *ff*, as clearly shown in the drawing.

Each leg of the frame terminates in an oblong base, *h*. The frame is susceptible of being ornamented with a variety of minor designs, which are neither shown nor claimed.

I claim the design for a frame for fire-place stoves, substantially as described and illustrated in and by the accompanying drawing.

In testimony whereof, I have signed my name to this specification, in the presence of two subscribing witnesses.

Witnesses:

ANDW. E. BOSWELL,
CHARLES G. FOSTER.
